UNITED STATES PATENT OFFICE.

AUGUSTUS NEWELL, OF CHICAGO, ILLINOIS.

GAS-HOLDER.

SPECIFICATION forming part of Letters Patent No. 428,125, dated May 20, 1890.

Application filed June 15, 1889. Serial No. 314,511. (No model.)

To all whom it may concern:

Be it known that I, AUGUSTUS NEWELL, a citizen of the United States, residing at Chicago, in the county of Cook and State of Illinois, have invented certain new and useful Improvements in Gas-Holders; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to gas-holders having metallic tanks in lieu of the ordinary tanks consisting of pits dug in the earth and lined with masonry and cement. The latter construction has always been expensive and troublesome. It is expensive to excavate a pit of sufficient dimensions and wall the same, and it has always been a difficult task to seal such pit against the ingress or escape of water. In many localities where holders are located the ground is full of water, and frequently there are springs tapped by the excavation, so that there is a constant tendency of the water to rise and hinder the building of the tank. In pits of this size used for such tanks it is extremely difficult to so line the same as to keep out or retain the water. If a complete lining of cement is made, often it is but a little while until the same is broken or cracked in one or more places, so that the water enters or escapes, according to the situation. Moreover, when the tank is a pit in the ground the parts which need repairing are largely inaccessible, while in works where all the apparatus is constructed above ground, surrounded by plenty of light and air, it is an easy matter for the engineer to control the condition of the apparatus and maintain it in a proper state. Since the gas-holder tanks form a part of the most expensive apparatus which enter into the construction of gas-works, it is of great importance that both cost and facility of construction and maintenance receive the most careful consideration.

It has been the custom to repeat the old and well-known construction of masonry tanks in almost every instance where a new gas-holder has been erected, although it is well known that the guarantee for perfect

construction and proper results is exceedingly doubtful, even in good building ground. Numerous instances of defective masonry tanks prove the correctness of this assertion. For this reason it seems very necessary to look forward to a construction of gas-holder tanks which will overcome the above objections.

It is very difficult to estimate the probable cost of a masonry tank previous to its construction when the same is to be executed in treacherous ground, whereas the cost of a foundation to support the iron tanks is determined with comparative ease and provided for. In very bad ground piling becomes necessary, and, according to its formation, either wood, sand, or concrete piles must be used. The character of such piling, if an iron construction is to be used, is easily determined; but proper tests to determine what is required for a masonry construction can only with difficulty be obtained, owing to the increased depth. In consequence of the unreliability of these tests it frequently becomes necessary to resort to piling after the excavations for the tank have been made when the same had not been contemplated in the estimates. In other cases where water and quicksand become factors to be dealt with large expense is incurred in providing steam-boilers and pumps and in keeping them in operation during the construction of the tank. This expense is not infrequently supplemented by the necessity of sheet-piling. With the added expense is coupled the delay in completion, and many engineers who have been confronted with these obstacles have been compelled to spend double the time counted upon in the construction of the gas-holder tank, and during this time could not avail themselves of the probably much-needed additional storage capacity.

The time of completion for the construction of an iron tank of average dimensions can, with certainty, be established to within a week or two, and in large tanks to within two or three weeks, and when compared with the time required to construct a brick tank under the most favorable conditions in good building ground can be accomplished in from twenty to thirty per cent. less time than that required for the masonry tank.

It is the opinion of many engineers that a masonry tank of large dimensions should be constructed the year previous to the construction of the holder. This has no doubt many advantages, but again adds to the cost of construction on account of the necessary protection against frost and deterioration during the winter months, the ordinary protection during this time being the filling of the tank with water, which of course has to be pumped out previous to the construction of the holder. When properly constructed and carefully executed, it is reasonable to expect that iron tanks will have the desired results as to perfectness; but this cannot be asserted of the masonry tank, and often its defects are not developed until it is being filled with water, when in many instances apparently good and sound tanks show a large amount of leakage. There are many causes which may render the masonry tank defective before the holder is completed. When much water is excavated and pumping has to be continued after the tank is completed to admit of the erection of the iron-work, it is possible that the back filling of the tank-wall near its base is undermined, thus forming a receptacle for the water that penetrates the masonry work at this point, and is, no doubt, in many instances the cause of leaks that appear unaccountable. As the exterior of the tank is inaccessible, the most careful examination of the interior of the same would not detect the defect. These conditions do not exist in the construction of iron tanks, and should any defects be developed in the latter they are at once discernible and easily remedied.

Establishing a masonry tank, particularly a large one, frequently depreciates the value of the ground in which the tank is located. In our large and rapidly-growing cities, where ground in favorable locations increases in value with the growth of the population, a lot of ground occupied by a masonry gas-holder tank remains comparatively valueless, as it is not applicable to other uses without considerable loss and expense of filling the excavation occupied by the tank; but iron tanks located above ground are susceptible of being taken apart and removed and reconstructed in another location, thus leaving the ground upon which they stood uninjured for other uses.

Cast-iron tanks in the form of a large vat or cheese-box having a flat horizontal bottom and upright wall have been heretofore used. It will be seen, however, that it is not practicable to make large tanks of cast-iron; but tanks of this shape have also been built up of wrought-iron or steel plates riveted to each other. In such tanks the interior space to be filled with water is practically the same as though the tank were constructed of masonry in the old way. In such construction a large volume of water is needed, and the whole mass must be of the full depth of the tank. Therefore the tank is of enormous weight,

and a substantial foundation must be provided for the entire area of the tank in the same manner that a strong foundation is needed for the entire area of the masonry tanks. If piling is needed at all, it must be provided over the entire area of the tank. If grouting and cement are used beneath the tank, they must be supplied over the entire area of the tank. All this is very expensive and requires the application of increased time, care, and skill. Furthermore, in such case, after the work has been completed, a large portion of the tank—viz., the entire bottom thereof—is rendered inaccessible.

My improvements apply to a gas-holder tank built up of wrought-iron or steel plates in annular or ring form, so that a relatively small volume of water is required to fill the tank, whereby the total weight of the tank is reduced, and so that only a circle of piling or other support need be provided as a foundation for the tank, thus rendering almost the entire surface of the tank accessible for inspection, painting, and repairs.

The details of my invention will be understood from an inspection of the accompanying drawings and an examination of the following description and claims.

In said drawings, Figure 1 is a vertical central section of a gas-holder embodying my improvements. Fig. 2 is a horizontal section of one-half of the holder shown in Fig. 1. Fig. 3 is a bottom view of one-half of said holder. Fig. 4 is a horizontal section through an annular hot-air chamber placed at the seal between the upper and lower sections of the holder. Figs. 5, 6, 7, 8, 9, and 10 are detail views. Figs. 11 and 12 are perspective detail views showing the construction of the inner wall of the tank.

The holder is represented as being composed of a tank and two lifting-sections, said lifting-sections being provided with the usual interlocking water seal.

A is the upper section of the holder. B is the lower section, and C is the tank. Said tank is in the form of an annular trough, and the space compassed by the inner wall is covered by the roof C', the periphery of which is joined to the upper edge of said inner wall. Thus there is an open space below said roof and within said annular trough. The principal part of the foundation must therefore be in the form of a circle beneath the annular trough. D is such a foundation. This may be of any suitable kind to meet the requirements of the particular situation chosen for the holder. If the site for the holder is upon very firm ground or upon rock, ordinary stone abutments on a continuous wall, like the basement of a house, may be used; but if the site is upon soft ground, as over a bog, pond, or stream, piles may be used, as shown in the drawings. D' D' are such piles, and D² are caps resting upon the ends of the piles. Said piles may be arranged in a continuous series or in groups, according to the size of

the piles, the character of the ground, and the dimensions of the holder. The drawings show said piles set in groups at intervals under the trough of the tank. The upper line 5 of the foundation may be even with or just above the ground-line, or where the holder is to be set over a bog or pond or stream the foundation may rise considerably above the ground or water line.

10 In Fig. 1, D³ is the ground-line, a small space being shown between the ground-line and the upper line of the foundation, so that the base of the tank does not quite reach the ground. In either of the arrangements suggested 15 all the space between the base of the holder and the ground or water line may be suitably inclosed. When a continuous foundation-wall is used, such wall of course makes the inclosure, and may be provided with windows and with doors, if the base of the tank is sufficiently far above the ground-line to admit doors; and if there is not sufficient space for doors a passage, as D⁴, may be excavated and provided with descending and 20 ascending steps. The object in inclosing the space around the base of the tank is to protect the interior from the weather. The object of the windows is to afford light to the interior, and the object of the door or doors 25 is to afford workmen access to the interior.

The tank C is composed of upright walls C² 30 and the horizontal bottom C⁴, said upright walls being set apart sufficiently far to make room for the walls of the sections A and B 35 and the guide-rollers, to be hereinafter described, and to make room for workmen when it is desired to paint or repair the said walls. The walls C² and C³ and the bottom C⁴ may be continuous metal, or said bottom may be 40 trough-formed and receive the lower edges of the walls C² and C³, as shown in Fig. 8. It will be seen that in this form of tank the quantity of water required to fill the tank is very much less than is required in the ordinary 45 vat-form tanks, and that only sufficient water is required to immerse the walls of the sections A and B. In the massive holders which it is now customary to construct this constitutes an enormous difference. In a holder 50 having a diameter of one hundred feet the section of the water-tank need be only about three feet. The total weight of the tank is thus reduced by about three hundred and fifty to four hundred tons per foot of altitude. It 55 is of great importance that the parts of this tank be made strong and durable, and yet, for the sake of saving expense of construction, it is desirable to reduce the quantity of metal used as much as may be. With this 60 object in view I have devised the form of construction shown in the drawings. The wall C³ is to be built up of rectangular plates c³, meeting at their horizontal edges. Over the joint formed by the meeting of the horizontal 65 edges is laid a strip of angle-iron c⁴ and riveted to said edges, the free flange of the angle-iron being above and projecting horizon-

tally toward the interior of the tank. Thus the vertical flange of the angle-iron unites the two edges of the plates c³ and seals the joint, 70 while the horizontal flange stands edgewise to the lateral strain of said wall, so that it stiffens the latter and enables it to resist the pressure of the water between the walls C² and C³. By reason of this horizontal flange 75 of the angle-iron I am enabled to materially reduce the thickness of the plates c³. It is to be noted that the pressure upon the inner wall C³ tends to collapse and buckle the latter and that the strain thereon is not a tensile strain, as is the case with the outer wall C². For this reason stiffness or rigidity instead of tensile strength must be provided for the inner wall. This is carried out further 80 by means of upright T-columns E, placed 85 with their heads over the vertical joints formed by the meeting edges of the plates c³. Rivets e join the heads of said columns to the plates c³ and seal said joints and bind said columns to said plates. Thus the web constituting the body of the column is placed 90 edgewise to the wall C³ and the pressure exerted by the water against the wall. Said columns should extend between the angle-irons c⁴ and from the bottom to the top of 95 said wall C³. Thus the horizontal flanges of the angle-irons c⁴ will extend against the sides of the body of the column E. Further rigidity is secured by pieces c⁵, of angle-iron, arranged horizontally against each side of the 100 column E upon the horizontal flange of the angle-iron c⁴ and riveted to said flange and said column by rivets e', whereby the breadth of said flange is made continuous horizontally around the entire wall C³. The vertical tread 105 F for the wheels L' may also be placed opposite a portion or all of the columns E and secured by the rivets e e'. Said tread will then add additional strength to said wall and will receive the guide-rollers of the lower section 110 of the holder, as will be described farther on. (See Fig. 5.) In Fig. 6 said tread is shown as a part of the column E, said column and said tread having been rolled in a single piece in a 115 rolling-mill, the web f connecting the two, and the vertical edges of the plates c³ abut against said web. In such form the web f may be sufficiently wide to make a space larger than the thickness of the plates c³, so that different thicknesses of said plates may be inserted 120 between said column and said tread. When the plates and said column have been riveted by means of the rivets e, a packing f', of lead or other suitable material, may be inserted between the face of the tread and the 125 adjacent plate c³ to further seal the joint along said column. The roof C' is also to be built of plates of any suitable form and may have the joints constructed in any desired way. For the purpose of strengthening said 130 roof angle-irons c' may extend in concentric circles along the lower side of said roof, with the depending flange of the angle-iron on the side toward the outer edge of said roof. G G

are bracing-rods resting against said angle-irons c' and extending obliquely downwardly and outwardly and resting by their lower ends upon the horizontal flanges of the angle-irons c' . Said bracing-rods are preferably parted and the ends formed by such parting inserted in suitably-threaded turn-buckles G' . The meeting ends of said bracing-rods and the turn-buckles are preferably right-
10 and-left threaded, so that by turning the turn-buckles in the proper direction the rod will be suitably lengthened to give the desired support and shape to the roof C' . Fig. 7 shows in detail one end of one of said bracing-rods and a preferred manner of connecting the same to the angle-iron. In this case the bracing-rod is a common iron tube, and is secured above and below by a block of iron G^2 , having a projection G^3 extending into
15 the upper end of the rod and having an oblique face resting against the flange of the angle-iron, and is secured to such angle-iron by means of a screw g^3 . The tendency of these bracing-rods is not only to support the
20 roof C' , but also to sustain the wall C^3 against inward pressure. Braces G , of wood, may be used.

H is a gas-induction pipe leading from the generating apparatus (not shown in the drawings) horizontally beneath the tank and thence upward through the roof C' .

I is the gas-ejection pipe leading from the roof C' downwardly below the lower portion of the tank and thence horizontally out to the main. (Not shown in the drawings.) A convenient arrangement is to couple the horizontal portions of the pipes H and I to elbows h and i , cast integral with the block H' , suitably supported from beneath and joining
35 the upright portions of said pipes to the upper ends, respectively, of said elbows. The upper ends of said pipes H and I have, respectively, a lateral flange h' and i' , through which and said roof bolts h^2 and i^2 extend.
40 The block H' , being supported from below, supports the upright portions of said pipes, so that the latter form additional supports for the roof C' . It is to be noted that these gas inlet and outlet pipes are entirely accessible at all times
45 for the purpose of inspection or repair or for replacing. This is an advantageous feature. In the case of the ordinary masonry tanks these pipes are buried in the ground and extend upwardly through the body of water in
50 the tank, so that they are inaccessible. Then if they need repairs it is extremely difficult to attend to them, and if they need replacing the work requires so much time as to make replacing impracticable as a business transaction.
55 For example, if the business of a gas-plant has increased to such an extent as to require larger inlet and outlet pipes to carry the volume of gas consumed, it might take a week or more to take up the old pipes and insert new ones, during which time the plant
60 would have to be idle and the city be without gas. It would be disastrous to a gas company

to shut down in this way for such a period of time. Their only course would be to build a new tank and holder with the large pipes, getting such new holder ready for use without stopping the works. This is not a mere fancy, but has actually occurred in practice. By my arrangement of apparatus a new and larger set of pipes may be arranged at leisure ready for making the connections. Then during a few hours the old pipes may be disconnected and the new ones connected.

Additional bracing-rods G may be placed vertically on suitable supports below and extend upwardly against the lower side of the roof C' , and indeed, if desired, the entire roof may be supported in this way. The wall C^2 is also to be built up of metal plates c ; but these may be joined at their meeting ends in any desired way. In the drawings, Fig. 2, they are shown as meeting at their vertical edges and as being joined by means of rivets to an overlapping strip c^2 , excepting at the upright guide-columns J . Said guide-columns are similar to the columns E , applied to the wall C^3 , and are applied in the same way, and have on the inner side of the wall C^2 a tread J' , which forms the counterpart of the tread F , applied to or forming a part of the opposite column E . The opposite treads F and J' form a way for the lower guide-rollers of the holder. L and L' are said guide-rollers. These are mounted in the ends of the horizontal shoe L^2 , which shoe is suitably secured to the lower edges of the section B of the holder, and is of proper length to cause said rollers to fit against the adjacent treads. It is to be observed that by this construction I am enabled to use two guide-rollers instead of one, and that by using said guide-rollers I sustain the wall of the movable section where they are applied against both inward and outward movement. In the common form of holder these guide-rollers are applied singly and only against the outer wall of the tank, so that the roller at any one point holds that portion of the movable section against outward movement, but not against inward movement, so that one side of the movable section of the holder is dependent upon the rollers on the extreme opposite side, seventy-five or one hundred feet away, to be held against inward movement. It will be seen that in such case, even if the rollers on the extreme opposite side endure the strain, the walls of the section may yield enough by reason of their elasticity to allow the portion of the wall against which there is pressure—as, for example, from wind—to move inwardly. My inner rollers L' act directly to sustain the portion of the wall to which they are attached against inward movement. Thus the holder is made much more stable and to a very large extent freed from strain, so that it may be constructed of lighter material and will endure longer.

The upper portion of the section B has the ordinary rollers b bearing against the tread

J', and the upper portion of the section A also has similar rollers *a* bearing against the tread J'.

In order that the water in the annular tank C may not freeze during cold weather, I provide the induction-pipe M, which extends horizontally beneath said tank and then opens upwardly toward the roof at or near the middle of the interior space within the tank. Through such induction-pipe hot air is driven from a suitable source of supply. On escaping from said pipe the hot air will rise from the pipe and meet the roof of the tank, and thence spread radially toward the outer portion of the interior of the tank, and thence, by reason of its greater weight derived from cooling and by reason of the pressure from the other air forced from the pipe M, it descends along the wall C³ and passes out horizontally beneath the bottom of the tank C at such places where openings are provided. Thus a constant flow and movement of warm air are maintained. If the cold is only moderate in intensity, the air may be driven slowly through the pipe and the interior of the tank sufficiently fast to impart a large quantity of heat to the walls of the tank. It is to be noted that by this arrangement the hot air passes over the entire surface of the wall C³, and also over a considerable portion of the bottom of the tank, and that in rising, (since it is lighter than the outer air,) after passing horizontally outward below the bottom of the tank, it will rise along the outer wall of the tank and still further impart warmth to the tank through the outer wall C², or at any rate by rising along said outer wall it will to a considerable extent keep the outside cold atmosphere away from the exterior of the tank. While this method of imparting warmth to the water in the tank is effective and economical, it has the further merit of being entirely safe. The hot air may be brought from such distance from the holder that there is no danger of igniting the gas and causing the explosion of the holder. For this reason this method is regarded as preferable to any other.

When the holder is filled sufficiently to cause the interlocking of the two sections A and B and the lifting of the upper portion of the lower section out of the water in the tank C, there is danger during cold weather that the water forming the seal between the sections A and B will freeze. I have provided for warming this water by means of hot air or steam. Either will answer the purpose. Each is a gaseous body and will flow readily through the passage O. In Fig. 1 the passage O is shown as formed along and in contact with the upper edge of the section B in such manner as that a portion of the wall of said passage is also the wall of the section B adjacent to the seal formed between the sections A and B. Fig. 4 shows a horizontal section through the chamber O. At a suitable point said passage O has a partition o, and on one

side of said partition is located an inlet-coupling O', which receives a flexible conductor O², leading from a source of hot air or from a steam-supply. O³ is an outlet on the opposite side of the partition o. With the exception of said inlet and outlet the passage O is closed. Thus the air or steam may enter through the inlet O' and follow in the direction of the arrows all the way around the holder and then escape through the outlet O³. This flow of the heated gaseous body (air or steam) adjacent to the seal warms the metal in the water and prevents the freezing of the seal. By means of the flexible conductor O² the section may move up and down without breaking the connection between the passage O and the source of hot air or the steam supply.

I claim as my invention—

1. In a gas-holder, the combination, with a movable section, of an annular metallic tank having the space between the upper edge of its inner wall closed by means of a roof, a gas-induction pipe and a gas-ejection pipe extending horizontally beneath said tank and rising to an opening through the roof, and a hot-air-induction pipe extending horizontally beneath said tank and opening into the interior space inclosed by said tank and roof, suitable openings being provided at the bottom of said tank for the escape of the hot air introduced through said hot-air-induction pipe, substantially as shown and described. 100

2. In a gas-holder, a movable section provided with inner and outer rollers and a tank provided with inner and outer treads for said rollers, substantially as shown and described. 105

3. In a gas-holder, a movable section having shoes L applied to its lower edge and bearing rollers at their ends and a tank provided with opposite vertical treads for said rollers, substantially as shown and described. 110

4. In a gas-holder, the combination, with a movable section, of an annular tank to receive said section, said annular tank having on the inner face of each of its walls vertical treads, and the lower edge of said movable section having rollers arranged to run upon said treads, substantially as shown and described. 115

5. In a gas-holder comprising an annular tank and a movable section, a vertical tread on the outer wall of said tank, a similar tread placed on the inner wall opposite the tread on the outer wall of said tank and within the movable section, and a pair of rollers attached to the lower edge of the wall of said movable section and fitted to run upon said treads, substantially as shown and described. 120

6. In a gas-holder, the combination, with a movable section, of an annular tank to receive said section, said annular tank having on the inner face of its outer wall a vertical tread and on the opposite face of the inner wall of said tank a similar tread opposite the tread on the outer wall, a shoe L², applied to

- the lower edge of said section, and a roller applied to each end of said shoe and against said treads, substantially as shown and described.
- 5 7. In a gas-holder, the combination, with a movable section, of an annular tank whose inner wall is composed of metallic plates having their horizontal edges joined by means of an overlapping angle-iron and their vertical 45 meeting edges joined by a vertical column, the ends of the horizontal flange of said angle-iron being joined to the body of said column, substantially as shown and described.
- 10 8. In a gas-holder, the combination, with 50 the movable section provided with rollers, of an annular tank having its inner wall strengthened by upright columns, and said columns having combined with them a guide-roller tread, substantially as shown and described.
- 15 9. In a gas-holder, the combination, with 55 the movable section provided with rollers, of an annular tank, the inner wall of said tank being comprised of metallic plates whose vertical meeting edges are joined by means of a column, and a roller-tread extending over the vertical edges of said plates, substantially as shown and described.
- 20 10. In a gas-holder, a movable section provided with rollers and an annular tank for 60 receiving said movable section, the inner wall of said tank being composed of metallic plates whose vertical meeting edges are joined by means of a column having a web f' , and plates being riveted to said column, substantially as shown and described.
- 25 11. In a gas-holder, an annular tank and a 65 movable section provided with rollers and extending into said tank, said annular tank having its inner wall composed of metallic plates 70 whose vertical meeting edges are joined by a
- T-column having formed upon it a web f' , extending between said plates and joined to a tread F for said rollers, said plates being riveted to the head of said column, and the horizontal meeting edges of said plates being 45 joined by an angle-iron, the ends of the horizontal flange of the angle-iron being joined to the body of said column, substantially as shown and described.
12. In a gas-holder, an annular tank and a 50 movable section provided with rollers and extending into said tank, said annular tank having its inner wall composed of metallic plates, and having the meeting vertical edges of said plates joined by means of a T-column, a web 55 f' , extending between the edges of said plates and supporting a tread F for said rollers, and the edges of said plates being riveted to said T-column, and a suitable packing being driven between said plates and said tread, substantially as shown and described.
13. In a gas-holder, the combination, with a movable section arranged to join by its upper portion to the lower portion of a section above it by means of the ordinary water seal, 65 of a closed passage O , extending along and in contact with the upper portion of the lower section, and having a flexible conductor leading into said passage, and having a suitable outlet near the point at which said flexible 70 conductor is joined to said passage, substantially as shown and described.
- In testimony whereof I affix my signature, in presence of two witnesses, this 24th day of May, in the year 1889.
